(Cl. D26—1)

To all whom it may concern:

Be it known that I, Wayne T. Gossard, a citizen of the United States and resident of the city of Los Angeles, county of Los Angeles, State of California, have invented a new, original, and ornamental Design for an Electrical Plug, of which the following is a specification, reference being had to the accompanying drawings, forming a part thereof, in which:

Fig. 1 is a top plan view of an electrical plug, showing my new design;

Fig. 2 is a side view;

Fig. 3 is a front end view;

Fig. 4 is a rear end view; and

Fig. 5 is a bottom plan view thereof.

I claim:

The ornamental design for an electrical plug, substantially as shown.

WAYNE T. GOSSARD.
